UNITED STATES PATENT OFFICE.

IVAR A. OLSEN, OF MINNEAPOLIS, MINNESOTA.

WALL-LINING.

SPECIFICATION forming part of Letters Patent No. 793,021, dated June 20, 1905.

Application filed February 4, 1905. Serial No. 244,682.

To all whom it may concern:

Be it known that I, IVAR A. OLSEN, of Minneapolis, in the county of Hennepin and State of Minnesota, have invented certain new and useful Improvements in Wall - Linings, of which the following is a full, clear, and exact description, reference being had to the accompanying drawings, which form a part of this specification.

10 My invention relates to the construction of wooden buildings; and it consists in providing portable wall-lining through the use of which dead-air spaces may be provided between the timbers constituting the frame, (the studding, joists, and rafters,) thereby rendering the walls, floors, and roof impervious to the air.

To this end my invention consists in so fashioning a cellular wall-lining as to make of it 20 a transportable article of manufacture.

In the drawings referred to, Figure 1 is a horizontal section of a wall furnished with my cellular wall-lining; Fig. 2, a vertical section of a floor furnished therewith; Fig. 3, a perspective of a portion of my lining cut from a strip; Fig. 4, an end view of my cellular wall-lining folded, and Fig. 5 a roll or bundle of my cellular wall-lining as when ready for shipment.

30 Similar letters refer to similar parts throughout the several views, A being my cellular wall-lining, B the studding to which it is affixed in a wall, and C the joist to which it is affixed, as in a floor.

35 My wall-lining A consists of two or more strips of paper, cloth, or other fibrous material of unequal widths, stitched, cemented, or otherwise united at their longitudinal edges, as shown by dotted lines *a*, as shown in Fig.

40 3, said strips being respectively creased intermediate their width, (preferably midway between their opposite edges,) as shown by creases *b* in Fig. 1, the narrower strip *c* being of sufficient length to reach from one 45 piece of joist to another, from one piece of studding to another, or from one rafter to another, exclusive of the united edges lying outside the dotted lines *a*, (at which the lining is laterally bent when securing it in place.)

50 I affix my cellular wall-lining in place as

follows: The frame of the building having been erected, the floor-boards nailed to the joists, the sheeting nailed to the studding, and the roof-boards nailed to the rafters, I measure the distances lying between the oppositely-faced sills when for floors, between the plates and the sills when for walls, between the ridge-pole and the plates when for roofs, and cut my lining to fit into these several compartments. These strips I respectively insert 60 between the joists, studs, or rafters and secure them in place as follows: Taking a strip of my lining I bend one of the longitudinal edges thereof along the dotted line *a*, lay the laterally-bent portion thereof against the side 65 of one joist, stud, or rafter, (as the case may be,) lay a cleat *d* thereon, (straps of lath may be substituted for cleats as long as the lining-strips,) and drive the nails *e* through the cleats, through the united and bent portion of the 70 lining, and into the timber, thus securing it in place at one edge. I then extend the lining across the intervening space to the oppositely-faced timber, (the joist, stud, or rafter, as the case may be,) to which I secure it in like 75 manner by means of other cleats *d'* and other nails *e'*, as shown in Figs. 1 and 2.

It will be seen that as the narrower strip of paper *c*, constituting one leaf of the bifolds of my wall-lining, is adapted to extend from 80 one joist to joist, from stud to stud, or from rafter to rafter, that the wider strip of paper *f*, constituting the other leaf of the bifold, must needs be deflected and lay separate and apart from the first-named leaf *c*, and it is 85 through having these strips of paper of unequal widths that the wider recedes from the narrower and that the dead-air spaces between them are formed.

What I claim as new, and desire to secure by 90 Letters Patent, is—

1. As a new article of manufacture, a wall-lining consisting of multiple folds of paper or other fibrous material of different widths, said folds being united at their longitudinal edges 95 and creased intermediate their length said united edges being adapted to lateral deflection, and to be secured to oppositely-faced timbers, in the manner, and for the purposes herein shown and described.

2. As a new article of manufacture, a wall-lining fashioned of multiple strips of unequal width, said strips being united at their parallel longitudinal edges, and creased intermediate their width, thereby providing dead-air spaces intermediate the said strips, through the unequal deflection of the respective strips, substantially as shown and described.

3. As a new article of manufacture a bifold of paper, cloth, or other fibrous material the leaves of which are of unequal width having the

parallel longitudinal edges of the two leaves united; and each being creased intermediate its width, thereby providing for unequal deflection of its leaves, and for an intermediate dead-air chamber, substantially as shown, and for the purposes specified. 15

IVAR A. OLSEN.
